UNITED STATES PATENT OFFICE.

THOMAS OLINGER AND FRANK STALKER, OF HOLLAND, MICHIGAN, ASSIGNEES TO
HOLLAND LIGHTING AND SPECIALTY COMPANY, OF HOLLAND, MICHIGAN, A
CORPORATION OF MICHIGAN.

VETERINARY SURGICAL TABLE.

1,357,417.

Specification of Letters Patent.

Patented Nov. 2, 1920.

Application filed March 25, 1919. Serial No. 285,138.

To all whom it may concern:

Be it known that we, THOMAS OLINGER and FRANK STALKER, citizens of the United States of America, residing at Holland, in the county of Ottawa and State of Michigan, have invented certain new and useful Improvements in Veterinary Surgical Tables; and we do hereby declare the following to be a full, clear, and exact description of 5 the invention, such as will enable others skilled in the art to which it appertains to make and use the same.

This invention relates to veterinary surgical operating tables, particularly tables 15 adapted for use in caring for small animals, the present invention being an improvement over that shown in a former application, Ser. No. 210,976, filed Jan. 9, 1918, for surgical operating table, by Thomas Olinger.

20 It is an object and purpose of the invention to provide a table consisting of two parts which may be independently adjusted with relation to each other and the support which carries the table, and thereafter held rigidly 25 in any position of adjustment, a particularly strong and rigid construction being made. A further object is to provide a particularly novel means of adjustment for the parts of the table, and one which can be very readily 30 and easily operated, while the manufacturing cost is greatly reduced over the construction shown in the application above noted. These features together with many others will appear fully and in detail as the description progresses, reference being had to 35 the accompanying drawings showing a preferred and practical embodiment of the invention, in which drawings,

Figure 1 is a side elevation of the table, 40 Fig. 2 is an end view of the table and upper portion of the support therefor.

Fig. 3 is a fragmentary vertical section through the support and showing the means of angular adjustment of the table as a 45 whole, and

Fig. 4 is a fragmentary enlarged side elevation, partly in section, illustrating the adjustable connection of the table parts to its immediate supporting means.

50 Like reference characters refer to like parts in the different views of the drawings.

The table as a whole is carried and supported at the upper end of a hollow column 1 which is equipped with a plurality of

diverging legs 2 at its lower end, the same 55 having casters or the like to permit ready movement of the column over the floor. The upper end of the column is divided, making two upstanding spaced apart arms 3 to the upper ends of which a bar 4 is pivotally 60 mounted at its middle as indicated at 5. A sector 6 is cast integral with the bar 4 and passes between the arms 3 of the column, being provided with a plurality of spaced apart notches 7 in its outer edges as shown. 65

In the upper end of the column a U-shaped member 8 is inserted, the upper ends of the legs thereof being connected by a cross bar, the ends 9 of which extend beyond the sides of member 8 and rest on the 70 column between the lower ends of the arms 3. Adjusting screws 10 pass through opposite sides of the column and thread into the opposite legs of the member 8, and it is evident that such member 8 may be adjusted 75 to different positions with respect to the column and held in any position to which adjusted.

A rod 11 passes freely through the bottom of the member 8 and the upper connecting 80 cross bar, its upper end being designed to enter any of the notches 7. At the lower end of this rod a wire 12 is connected and a coiled spring 13 is seated on the bottom portion of the member 8 and under compression acts to elevate rod 11 and force it into the notches. When a change in position of the sector 6 is desired, the rod 11 may be moved downwardly by operating a 85 foot lever 14 to which the lower end of the wire 13 is connected, said lever being pivotally mounted at one end on one of the legs 2. The adjustment of the member 8 described is for the purpose of adjusting the upper end of the rod 11 to enter the 90 center notch 7 properly so that the table carried by the bar 4 shall be perfectly horizontal, it being evident that variations due to shrinkage in casting, or from other causes, in the position of the central notch 7 may 95 be readily compensated by this adjustment.

At each end of the bar 4 a bracket 15 is secured, each having two spaced apart upwardly extending legs 16 which are pivotally connected to the inner ends of bars 17 100 serving as supports for the two parts 18 of the table. These parts 18 are of sheet metal, the adjacent edges of which are turned 105

downwardly around the inner ends of bars 17 as indicated at 19, there being formed an open slot between the table parts which extends the entire length of the table. This structure furnishes an open drain through which matter may pass to a drain trough 20 disposed lengthwise of and below the slot and resting on the brackets 15 between the legs 16. The trough is held against removal by a hook 21 which may detachably connect with a suitable eye on one of the legs 16 as shown in Fig. 4, but on disconnection of the hook, the trough may be readily removed for cleaning. The outer edges of the table parts 18 are bent and formed as indicated at 18^a making vertical outer surfaces to which hooks or the like of conventional form may be attached for the purpose of connecting with securing ropes or the like used to hold the animal on the table. Hooks 22 are connected at each end of the drain trough for supporting a pail or like device into which the drain trough may empty.

25 Two levers 23 are placed with their inner portions side by side at each end of the bar 4, each of said levers being formed at its inner end with a notched sector 24, the notches being spaced apart as shown. The levers at each end of bar 4 extend outwardly in opposite directions and each is pivotally connected to the end of the bar 4 by a stud 25 passing through a slot 26 in the lever. The studs 25 are of a size to readily enter 30 any notch in a sector 24, and the stud on which one lever 23 is pivotally mounted serves as a stop pin or stud for the other lever, entering a notch in its sector end 24. By reason of slots 26 in the levers 23, the levers may be pulled outwardly to disengage 35 from studs 25 with which their ends 24 engage, and the levers then turned to another position for the studs to enter other notches in said ends 24. The studs 25 are threaded, 40 one at each end receiving a locking hand wheel 27 and the other a nut 27^a, the hand wheel being operated to lock at least one of the levers 23 associated with a table part 18 against movement.

45 50 Each of the bars 17 is formed with a downwardly extending lug 28 at a point between its ends. A rod 29 is pivotally connected at its upper end to each of the lugs 28 and at its lower end has threaded connection with a member 30 connected to a lever 23, each of the levers being connected in this manner with a bar 17. The levers are formed with hand holds at their outer ends so that it is easy and convenient to 55 60 grasp the ends of the pair of levers at either side of the table, draw out on the same to disengage the ends 24 from the studs 25, tilt the table part 18 to any desired position, and push in on the levers to engage again 65 with the studs, after which the locking hand

wheel may be tightened to rigidly hold the part 18 in position and insure against possibility of disengagement. Either side 18 may be tilted independently of the other and to any preferred position or angle. And the table as a whole may likewise be turned about the pivot 5 to different angles to the horizontal.

70 75 The construction described is very strong and rigid and may be manufactured at a very low cost, much less than the one, application for patent on which is noted above. The adjustment of the member 8 is also of value in making it possible to adjust the table to an absolutely horizontal position without the necessity of carefully machining and fitting the slots 7 and the head 12 adapted to enter the same. All of these new features make the construction one of great merit and value.

80 85 We claim:

1. An operating table comprising two table members located with adjacent side edges spaced a short distance apart, a bar located lengthwise of and under the table members at the inner edges thereof, a bracket connected to each end of the bar, each of said brackets having two upwardly extending spaced apart legs, the table members having pivotal connection thereto, and means mounted on the ends of the bar and connected with the table members for moving either of said members to different positions about their pivotal connection to the legs of said brackets, and for holding said members in any positions to which they may be moved.

90 95 100 105 110 115 120 125 130 2. An operating table comprising a support including a bar, a bracket attached to each end of the bar above the same, each bracket having two upwardly extending spaced apart legs, two table members of sheet metal located with adjacent edges spaced a short distance apart, bars located transversely under each table member and secured thereto, the inner ends of the bars having pivotal connection to the upper ends of the legs of the brackets, two spaced apart studs extending from the ends of the first bar, two operating levers at each end of the first bar, said levers having inner ends placed side by side and each having a slot therethrough through which a stud passes, the inner ends of the levers being formed with notched sectors adapted to engage with the studs, and means connecting each lever with one of the bars under a table member, substantially as and for the purposes described.

3. An operating table comprising a main supporting bar, two table members located side by side with adjacent edges spaced a short distance apart, means for pivotally connecting each of the table members adjacent its inner edge to each end of the bar,

two levers located at each end of the bar and extending in opposite directions, the inner ends of said levers overlapping and having pivotal and slidable connection to the bar, means connecting the levers extending to either side of the bar with the table member above the same, and interconnecting means between the levers and the ends of the bar for holding said levers in any of a plurality of positions to which they may be moved with respect to the bar, substantially as described.

4. An operating table comprising a main supporting bar, a stud projecting from each end of the bar and to one side thereof, a lever located against each end of the bar and having a slot therein through which the stud passes, said lever being formed with a sector having a plurality of spaced apart notches therein, a second stud extending from each end of the bar at the opposite side thereof and adapted to enter any one of the notches in the lever, said lever being longitudinally movable to disengage from the stud, a second lever pivotally and slidably mounted on each of the second studs, said second levers lying against the first levers and having similar notched sectors at their ends in which notches the first studs are adapted to enter, two table members located above the bar and adapted to lie in the same plane with adjacent edges spaced

a short distance apart, means for independently pivotally connecting each table member to the bar, and a rod connecting each of the levers to a table member, two of the levers being connected to each table member, substantially as described.

5. An operating table comprising a hollow supporting column, said column having two upwardly extending spaced apart arms at its upper end, a bar located at the upper ends of said arms and pivotally connected thereto, said bar having a sector formed with a plurality of spaced apart notches passing between the arms, a U-shaped member located in the upper end of the column at the lower ends of the arms, adjusting screws passing through opposite sides of the column and threading into opposite legs of the U-shaped member, a foot lever pivotally connected at one end at the lower end of the column, a rod passing through the bottom of the U-shaped member and extending upwardly to the sector, being adapted to enter any of the notches in the sector, a spring seated on the U-shaped member tending normally to elevate the rod, a wire connecting the lower end of the rod and the foot lever, and a table carried by the bar.

In testimony whereof we affix our signatures.

THOMAS OLINGER.
FRANK STALKER.
